UNITED STATES PATENT OFFICE

154,882

DESIGN FOR A WATERING POT

Vincent A. Savarese, Philadelphia, Pa.

Application January 7, 1947, Serial No. 135,977

Term of patent 3½ years

(Cl. D35—3)

To all whom it may concern:

Be it known that I, Vincent A. Savarese, a citizen of the United States, residing at Philadelphia, in the county of Philadelphia and State of Pennsylvania, have invented a new, original, and ornamental Design for a Watering Pot, of which the following is a specification, reference being had to the accompanying drawing, forming a part thereof:

Fig. 1 is a perspective view of a watering pot showing my new design.

Fig. 2 is a side elevation thereof, and

Fig. 3 is a top plan view of the same.

I claim:

The ornamental design for a watering pot, as shown.

VINCENT A. SAVARESE.
